UNITED STATES PATENT OFFICE.

GREGGAR SMEDAL, OF LA CROSSE, WISCONSIN.

TYPE-WRITER ATTACHMENT.

1,149,792.

Specification of Letters Patent. Patented Aug. 10, 1915.

Application filed November 21, 1914. Serial No. 873,885.

To all whom it may concern:

Be it known that I, GREGGAR SMEDAL, a citizen of the United States, residing at La Crosse, in the county of La Crosse and State 5 of Wisconsin, have invented certain new and useful Improvements in Type-Writer Attachments, of which the following is a specification, reference being had to the accompanying drawings.

10 This invention relates to an improved attachment for typewriters, and has for its primary object to provide improved means for mounting and supporting a plurality of paper rolls for movement with the carriage 15 of the machine.

The invention has for another object to provide paper roll supports independently adjustable to receive rolls of paper of varying widths, and means common to all of the 20 supports for holding the adjustable parts thereof after being so adjusted.

The invention has for an additional object to provide improved means for preventing excessive rotation of the paper roll, 25 as the paper is pulled therefrom when the platen of the typewriter is turned.

It is an additional object of the invention to provide a vertically adjustable main frame, a horizontally traveling paper roll 30 frame mounted upon said main frame, and means for connecting the latter frame to the carriage of the typewriter for movement with the carriage.

The invention has for another specific 35 item of improvement a very simple and novel form of paper cutter whereby the paper sheet, after being written upon, may be detached from the roll.

With the above and other objects in view, 40 my invention consists in the novel features of construction, combination, and arrangement of parts to be hereinafter more fully described, claimed, and illustrated in the accompanying drawings, in which,

45 Figure 1 is a front elevation showing my improved attachment arranged in operative connection with a typewriter; Fig. 2 is a side elevation thereof; Fig. 3 is a section taken on the line 3-3 of Fig. 2; Fig. 4 is a 50 vertical section taken on the line 4-4 of Fig. 3; Fig. 5 is an enlarged longitudinal section through the end of one of the paper roll cores showing the tension plug arranged

therein; Fig. 6 is an end elevation of said plug; Fig. 7 is a detail fragmentary perspective view of the paper guide and cutter; and Fig. 8 is a detail perspective view of one of the adjustable supporting members for one paper roll.

Referring in detail to the drawings, 5 designates a suitable base which is provided with rubber foot members or cushions 6 for frictional engagement with the table or desk upon which the typewriter is mounted. In this supporting base, spaced parallel vertical rods 7 are suitably secured at their lower ends. A bracket member 8 is provided with spaced openings and tubular depending arms or extensions 9 which are designed to receive the respective uprights or rods 7. 10 Upon this bracket member a horizontally disposed frame is secured. This frame includes spaced parallel metal bars 11 between the ends of which spacing sleeves 12 are disposed. The opposite ends of these 15 sleeves are interiorly threaded to receive threaded bolts 13. Additional sleeves 14 are also arranged between the parallel bars 11, and bolts 15 extend through the bracket member 8 and one of said bars and are 20 threaded into said latter sleeves, the other of the frame bars being secured to the opposite ends of said sleeves in the manner above described. A stop plate 16 is arranged between one of the frame bars 11 25 and the end of one of the spacing sleeves 12. This plate is formed with vertically disposed lugs 17 for a purpose which will be later referred to.

The bracket member 8 is held against 30 vertical movement upon the rods 7 after it has been adjusted by means of a pair of rods or bolts 18 which are loosely mounted for sliding movement in a horizontal passage or opening 19 formed in the body of 35 the bracket. The outer ends of these bolts are adapted to frictionally engage the respective rods 7 when their inner ends are engaged by the tapered shank portion 21 of an adjusting screw 20, said shank being 40 formed with a threaded extension 22 for engagement with a threaded bore or opening in the bracket.

Upon the horizontal frame above referred to, a paper roll carrying frame is mounted 45 for horizontal movement. This latter frame

includes end plates 23 of similar form, each having an upwardly extending arm 24 and a downwardly extending arm 25. The intermediate portion of this plate 23 is of substantially U-shape form to receive or accommodate the spaced horizontal bars 11. The forwardly extending intermediate portion of this U-shaped body of the plate is formed with an inwardly projecting arm or extension 26 which is disposed in spaced parallel relation to the forward frame bar 11. This arm or extension is formed with a longitudinal slot 27. A plate 28 is engaged upon the outer faces of these arms on the end members 23 and has its upper edge flanged as at 29, said flange engaging over the upper edges of the extensions 26. 30 designates additional forwardly extending roller supports, each of which includes a body plate 31 having a flange 32 on its upper edge to engage over the flange 29 on the plate 28. This body plate 31 of the roller support is also formed with a longitudinally extending slot 33 which is open at one of its ends. Bolts 34 are adapted to be inserted through the slots 33, openings 35 formed in the ends of the plate 28, and through the openings 27 in the extensions 26. On the outer ends of said bolts clamping nuts 36 are threaded. It is apparent from this construction, that the several elements of the roller supporting frame may be easily and quickly adjusted and securely held in their adjusted positions whereby paper rolls of various widths may be mounted therein. Upon the inner sides of the U-shaped body portions of the end members 23, bearing plates 37 are secured, in which the ends of transversely disposed axles 38 are journaled. 40 Wheels or rollers 39 are fixed upon the ends of these axles for engagement upon the upper edges of the horizontal frame bars 11 which constitute tracks. The rear wheels 39 are formed with peripheral grooves in which the edge of one of the frame bars fits, whereby transverse shifting movement of the roller supporting frame with relation to the relatively stationary main frame, is prevented.

45 The upper ends of the extensions 24 on the end members 23 are formed with rectangular notches or recesses 40 and the downwardly projecting extensions 25 of said members are provided with similar sockets or recesses 41. The relatively adjustable roller supporting members 30 also have such notches or recesses 42 formed in their forwardly projecting arms 43. In these notches or recesses 40, 41, and 42, the several paper rolls are mounted and supported in the manner which I shall now describe. The several paper rolls indicated at R are each wound upon a tubular core R'. A hollow sheet metal plug or shell 44 is longitudinally split as at 45 to provide opposed resiliently movable portions. One end of this shell is inwardly tapered as at 46 so as to facilitate its insertion into the end of the roll core R'. The opposite end of the split metal shell is formed with an enlarged circular head 47 70 provided with a central opening 48. The opposed portions of the shell 44, opposite to their separated edges, are inwardly extended to provide parallel portions 49 connected by a centrally located cylindrical enlargement 50 which is adapted to clampingly engage the shank of a bolt 51. The threaded end of this bolt projects outwardly through the opening 48 in the head of the resilient shell and upon the same a finger piece is engaged. This finger piece is formed from a plate having its ends 52 disposed in spaced parallel relation and knurled or roughened on their outer surfaces. The intermediate portion of the plate which connects these 85 spaced ends is offset as at 53, and formed with a central threaded opening for engagement with the threaded end of the bolt 51. This offset portion of the finger piece is of rectangular form and is adapted to be seated 90 in the notch of the roller supporting arm or member. Thus, the turning movement of the resilient shell or plug which is fitted into the end of the roll core is effectually prevented. The relatively movable opposed 95 portions of the sheet metal plug clampingly engage against the opposite sides of the roll core, and by frictional contact therewith, tend to retard the rotative movement of the roll. In this manner, excessive movement of 100 the roll, when the paper is pulled therefrom, is obviated, so that the paper is always taut and no slack will occur therein.

Upon referring to Figs. 1 and 2 of the drawings, it will be observed that my attachment is adapted to be arranged at the rear of the typewriter and, as illustrated, I have shown the device employed in connection with a typewriter of the make commonly known as "Underwood No. 5." Upon 110 the depending extension 25 of one of the roller supporting members 23, a plate 54 is pivotally mounted at one of its ends, as shown at 55. To the other end of this plate, an arm 56 is pivotally connected, the other 115 end of said arm being formed with a lateral extension 57 in which a suitable clamping device 58 is pivoted, as shown at 59. This clamping device is adapted to be engaged with the rear turned or beaded edge of the metal paper shelf or guide G which is mounted upon the movable carriage of the typewriter. When the arm 56 has thus been connected to the typewriter carriage, it will be apparent that in the step by step movement of the carriage, the roll carrying frame of my attachment is moved upon the horizontal supporting bars 11 to a correspond-

ing extent, thus shifting the paper rolls as the writing proceeds. I have also devised an improved combined guide and paper cutter for use in connection with the attachment. This device includes links 60 which are adapted to be adjustably secured at one of their ends to the roller supporting members 23 by means of the screws 61. Levers 62 are adjustably connected to the other end 10 of said links by the clamping screws 63, and on the forward ends of said levers the plates 64 are secured. Each of these plates is provided with an opening 65 having a reduced intermediate portion. In the relatively wide 15 outermost portion of this opening, the ends of a cutter bar 66 are adapted to be engaged. The inner portion of the opening 65 is of still greater width and receives the ends of a slightly bent or curved guide plate 67. An additional pair of levers 68 are adjustably held at one of their ends by means of set screws 69 upon the forwardly projecting roller supporting arms 43, and these levers are equipped upon their opposite ends 25 with a similar guiding and cutting device for the paper which may be employed in lieu of the one above referred to, when the roller support is lowered upon the frame to such a position as would prevent the proper 30 arrangement of the pivoted levers 62.

From the foregoing description, taken in connection with the accompanying drawings, the construction, manner of use, and several advantages of my attachment will be 35 readily understood. By the provision of the adjustable roll supports, it will be observed that paper of different widths may be mounted in the supporting frame. The paper from the three rolls is fed to the typewriter beneath the platen roll in the usual manner, the outermost paper sheet being disposed between the cutting blade 66 and the plate 67. The intermediate sheet which is drawn from the uppermost roll may be of 40 carbon paper so that an original and carbon duplicate will be produced. The traveling or sliding roller supporting frame being connected to the typewriter carriage in the manner above described, said frame will 45 readily move with the carriage as the writing progresses. After the writing is complete, the front paper sheet may be readily removed from beneath the platen roll and cut off cleanly from the paper and roll by 50 means of the knife or cutter 66, without disturbing the carbon or the duplicate copy. The front sheet is then again drawn down and engaged beneath the platen upon which another writing may be made.

It is often necessary to use papers of different widths in making bills or accounts, and for this purpose, it will be seen that 55 my invention is particularly advantageous. In such use, any one of the several widths

of paper may be drawn from the roll and 60 passed over the guide plate 67 and beneath the platen roller, so that the paper will be drawn only from this roll while the others remain idle. In this manner, it will be seen that I have produced a very convenient and 65 serviceable attachment, and one which is also comparatively simple in its construction and is applicable to various makes of typewriters now in common use. By means of my invention, the time and labor incident to 70 the making of large numbers of accounts, statements, bills, or the like, are greatly reduced.

While I have above referred to the preferred form, construction, and arrangement 80 of the several elements employed, it is to be understood that I do not desire to be limited thereto, but reserve the privilege of resorting to all such legitimate changes as may be fairly embodied therein without departing 85 from the spirit or scope of the invention as claimed.

Having thus fully described my invention, what I desire to claim and secure by Letters Patent is:—

1. A paper roll support including a relatively stationary horizontally disposed frame, a supporting standard therefor, a paper roll carrying frame longitudinally slidable upon said stationary frame and provided with 95 means for supporting paper rolls in superposed relation above and below the plane of said stationary frame, and means for vertically adjusting said stationary frame upon its support whereby the paper roll carrying 100 frame is raised or lowered.

2. A paper roll support including a frame embodying opposed supporting members provided with means for supporting a pair of paper rolls in superposed relation, additional forwardly projecting supporting members mounted upon the respective first named members and adjustable longitudinally with relation thereto to support a third paper roll in a plane intermediate the 110 superposed rolls, and means for holding the several supporting members against relative movement with respect to each other.

3. A paper roll support including a horizontally disposed stationary frame, a paper 115 roll carrying frame embodying spaced roll supports provided with bearings to receive and support between them a pair of paper rolls said supports being relatively adjustable, means on said roll supports mounted 120 upon the stationary frame for longitudinal travel, additional relatively adjustable paper roll supports to receive a third paper roll, and means common to the corresponding roll supports to retain the same in adjusted 125 relation with respect to each other and with respect to the complementary roll supports.

4. A paper roll support including a hori-

- zontally disposed stationary frame, a paper roll carrying frame comprising spaced roll supports having means to support between them a pair of paper rolls in superposed relation above and below the stationary frame said supports being relatively adjustable, rollers carried by said duplex supports to travel longitudinally upon the stationary frame, additional paper roll receiving arms, a common supporting plate for said roll supports and the additional supporting arms, and means for clamping the corresponding roll supports to said plate and securing the same in their adjusted positions with respect to each other and with respect to the complementary roll supports.
5. A paper roll support including a stationary track and a paper roll carrying frame consisting of a pair of supports each provided with rollers to travel longitudinally on the track, a plate connecting the supports, and means for adjusting the supports upon said plate toward or away from each other, each of said supports being provided with a plurality of paper roll receiving bearings.
6. An attachment for typewriters including a paper roll carrying frame, a support therefor upon which said frame is longitudinally movable, means for vertically adjusting the support and the roll carrying frame with respect to the platen of the typewriter, and flexible means carried by the roll support for detachable connection to the typewriter carriage to cause the roll frame to move longitudinally with the carriage, but permit of the vertical adjustment of said frame and its support without disconnecting the frame from the carriage.
7. An attachment for typewriters including a stationary frame, a paper roll supporting frame longitudinally reciprocal upon said stationary frame and embodying spaced supporting members, said members being provided with means to receive and support between them paper rolls above and below the horizontal frame, means for adjusting said members relative to each other, and means connected to one of the supports for detachable engagement with a typewriter carriage whereby the support is shifted longitudinally upon the stationary frame in the movement of the carriage.
8. An attachment for typewriters including a stationary support, a paper roll supporting frame longitudinally movable upon the stationary support and embodying means for supporting a pair of paper rolls in superposed relation above and below the stationary frame, additional forwardly projecting roll supports longitudinally adjustable upon said first named supports to receive a paper roll of a different width from the rolls mounted in said first named sup-
- ports, and means for detachably connecting the paper roll supporting frame to the carriage of a typewriter for movement therewith.
9. An attachment for typewriters including a stationary support, a horizontally disposed frame mounted upon said support, a paper roll carrying frame longitudinally movable upon said horizontal frame and provided with means for supporting a plurality of paper rolls, and means for vertically adjusting said horizontal frame and the paper roll frame upon said support to position the paper rolls with respect to the platen of a typewriter.
10. An attachment for typewriters including a vertically disposed support, a horizontal frame mounted upon said support, a paper roll frame longitudinally movable upon said horizontal frame and provided with means for supporting a plurality of paper rolls, means for detachably connecting said paper roll frame to the carriage of a typewriter for movement therewith, and means for vertically adjusting said horizontal frame and the paper roll frame upon said support to position the paper rolls with respect to the platen of the typewriter.
11. An attachment for typewriters including a vertical support, a horizontal frame mounted upon said support, a paper roll carrying frame longitudinally movable upon the horizontal frame and provided with means to support a plurality of paper rolls, means for connecting the paper roll frame to the carriage of a typewriter consisting of pivotally connected relatively movable elements, and means for vertically adjusting said horizontal frame and the paper roll frame upon said support to position the paper rolls with respect to the platen of the typewriter.
12. A typewriter attachment including a vertical support, a horizontal frame mounted upon said support, a paper roll frame longitudinally movable upon said horizontal frame, means for connecting said paper roll frame to the carriage of a typewriter consisting of a plurality of pivotally connected relatively movable elements, and means for vertically adjusting said horizontal frame upon the support to position the paper roll with respect to the platen of the typewriter.
13. An attachment for typewriters including a vertical support, a frame mounted upon said support, a paper roll carrying frame longitudinally movable upon said first named frame, means for detachably connecting the paper roll frame to the carriage of a typewriter, means for vertically adjusting the first named frame upon the support to position the paper rolls with respect to the platen of the typewriter, a plu-

rality of pairs of guide supports pivotally mounted upon the paper roll frame and adjustable with respect thereto and a combined paper guide and cutter adapted to be
5 removably mounted in either pair of the guide supports.

In testimony whereof I hereunto affix my signature in the presence of two witnesses.

GREGGAR SMEDAL.
